UNITED STATES PATENT OFFICE.

PIETER MIJER, OF NEW YORK, N. Y., ASSIGNOR, BY MESNE ASSIGNMENTS, TO THE TWO-TONE CORPORATION, OF NEW YORK, N. Y., A CORPORATION OF NEW YORK.

TWO-TONE TEXTILE FABRIC.

Application filed June 30, 1924. Serial No. 723,167.

This invention relates to improvements in textile fabrics having two-tone effects, that is to say, colored with one color or tone on one side thereof, and colored with a different color or tone on the other side thereof; such fabrics being heretofore made either by the double weaving with threads of different colors, or by using animal and vegetable fibres and so weaving the material that the animal fibres were exposed on one side of the material and the vegetable fibres were exposed on the other side of the material, after which the material was dyed in two baths, one which colored the animal fibres while the other colored the vegetable fibres. The present invention provides a textile fabric made of either animal or vegetable fibre or mixtures of both, which is one color or tone on one face thereof and a different color or tone on the other face thereof, and this irrespective of the direction in which the threads run or the relation of animal to vegetable fibres when a mixture of these is employed; more specifically, the invention provides a permeable textile fabric such as silk, cotton or linen of the kind ordinarily employed in commerce, which is colored one color or tone on one side and another color or tone on the other side; where the textile fabric is a mixture of animal and vegetable fibres such as silk and artificial silk, the surfaces will present the colors selected irrespective of whether one surface is mainly constituted by the artificial silk and the other by the natural silk.

The invention further contemplates textile fabrics having different color effects on one side thereof as compared with the color effects on the other side thereof, irrespective of whether the fabric is made of animal or vegetable fibre or mixtures of both, and irrespective of the preponderance of one or other type of fibre in one or other surface.

The invention will now be described with reference to the accompanying drawings in which—

Fig. 1 is a purely diagrammatic showing indicating a cross-section through a piece of fabric colored on both sides thereof;

Fig. 2 illustrates in purely diagrammatic form the depth of color when the textile fabric is thick;

Fig. 3 is a diagrammatic view of a "single-woven" fabric presenting the two-

tone effect in accordance with the present invention;

Fig. 4 is an enlarged sectional view of a "double-woven" fabric;

Fig. 5 is a thread from the fabric of Fig. 3;

Fig. 6 shows a fabric of vegetable fibres with an intermixture of animal fibres;

Fig. 7 is an exaggerated diagrammatic view of a portion of the improved fabric with a design printed thereon;

Fig. 8 is a diagrammatic view of a piece of accordion pleating made in accordance with the invention;

Fig. 9 illustrates longitudinal ambre and rainbow effects;

Fig. 10 illustrates stencil effects; and

Figs. 11 and 12 illustrate other effects.

Figure 13 is a section of one unit of a dyeing apparatus such as is described and illustrated in my copending application Serial No. 692,762, and which is referred to hereinafter in order that the process of making my improved textile fabric may be more readily understood.

Figure 14 is a longitudinal section along the line 14—14 of Fig. 13, and

Figure 15 represents diagrammatically in elevation certain apparatus which may be successively used in carrying out the process.

Referring first to Figs. 1 and 2, Fig. 1 represents a piece of thin silk such as a piece of flat silk, and Fig. 2 represents a thicker fabric such as a fabric used in rib-bois, etc. The materials illustrated in these figures are made of the same fibre such as silk, linen or cotton, and are colored on one side *a* with one color, and the other side *b* with another and different color or tone. The dotted line 20 in Fig. 1 indicates diagrammatically a zone where the two colors intermingle; it is not necessary, however, that the colors should intermingle in this zone; the dotted lines 21 and 22 indicate the extent of penetration of the color into the surfaces *a* and *b* of the thicker fabric of Fig. 2. The fabric and dotted lines are not here shown to scale and the drawing is merely illustrative that the different color dyes can either completely color the fabric throughout its thickness as in Fig. 1, penetrate to a more limited extent as in Fig. 2, or overlap in a central zone indicated by the

line 20 in Fig. 1. The permeable fabric is dyed by the process described in the copending applications Serial No. 692,762 filed February 14th, 1924, Serial No. 723,166 filed June 30, 1924, Serial No. 725,100 filed July 10, 1924, and Serial No. 692,763 filed July 16, 1924, all of which describe methods and apparatus for coloring permeable material, such as silk, with one color on one side thereof and with another color on the other side thereof, said colors in general coloring the surface on one side of the material substantially evenly and without the formation of spots or substantial streaks, without the color penetrating through to the other surface thereof, except where the effect of such penetration is especially desired to make a mixture with the color on the other surface thereof.

20 After the material has been dried or steamed and is otherwise treated in the manner usual in the art according to the finish desired, the material or silk presents the characteristic that the dye penetrates the surface to an extent desired depending upon the length of time that the material is exposed to the color cloud. This extent is preferably such that in the case of light fabrics, the penetration on both sides is sufficient to give the color body and to secure the desired coloring effect on the material, so that the color will not readily wash off or otherwise expose uncolored surfaces of the fabric, the effect of the aforesaid steaming is to fix or set the dye in the fibres of the fabric as is described in said copending applications so that the dye will be substantially fast in the fabric. The silk according to the invention has been washed, and the colors found to be substantially fast for practical commercial usage; where the color has penetrated into the silk in a predetermined amount it is actually penetrated by the dye, and thereafter set by steaming operation to such an extent that the silk possesses highly desirable qualities and compares with silk ordinarily in use. The fabric presents on each surface a homogeneously and differently colored face which makes it possible to employ the fabric for a large variety of commercial purpose; for example, lamp shades, ladies' blouses, in which the collars and cuffs are formed by turning over the material, umbrellas and other uses, some of which will be described and claimed in separate patent applications. Owing to the fact that the process is applicable to ordinary woven fabrics now upon the market irrespective of whether they are single or double-weave animal or vegetable fibres, the improved product presents the advantage that the silk material does not have to be specially woven for the dyeing; that is to say, silk woven for the ordinary dyeing processes can also be used for the present

process; the textile fabric made in accordance with the invention therefore differs from similar fabrics in the following points: (a) the surface of the improved dyed fabric (unless it is printed as described later) is substantially evenly colored or homogeneously colored, that is to say, the colored surface does not show to the naked eye a large number of small specks of color, but is a substantially evenly colored surface comparable as to its evenness to the surface resulting from the ordinary vat dyeing processes; (b) threads in the fibre which run from one surface to the other are colored one color near and at one surface and the other color near and at the other surface, so that a continuous cross-thread, if taken out of the fabric, will be found to be made up of a number of different colored portions. This is illustrated clearly with reference to Figs. 3 and 4. Referring to Fig. 3, the cross-threads 23 and 24 respectively on the surfaces *a* and *b* are colored different colors which either wholly or partly penetrate said threads; I have here indicated the zones by the dotted lines 21 and 22, showing the depths of the color penetration on the sides *a* and *b* from which it will be noted that portions of the cross-thread 25 are stationed some in one color zone, and some in the other, while other portions of the cross-thread are stationed in the intermediate zone between the dotted lines 21 and 22, and are uncolored. Fig. 5 shows a diagrammatic view of this cross-thread 25 removed from the fabric, from which it will be seen that same presents portions 26, for example, colored red, portions 27, for example, colored blue, and portions 28 which are not colored at all. In Fig. 4 I have shown a "double-woven" fabric with two sets of cross-threads and two sets of longitudinal threads; the longitudinal threads pass from one color zone into the other and present the characteristic that portions of said threads are colored different colors according to the color zone through which they pass.

The fabric therefore differs essentially from the well-known "double-woven" fabrics made up of different woven threads now on the market, and which present different colors on different sides; each thread of said "double-woven" fabric is of one color and is dyed before weaving; the improved product is also distinct from fabrics made of a mixture of animal and vegetable fibres in which all of the animal fibres are colored one color, while all the vegetable fibres are colored another and different color.

Referring to Fig. 6, I show in the upper view a diagrammatic representation of a piece of silk consisting of a mixture of artificial and natural silk fibres. The artificial silk fibres are woven to produce the design 29,

while the natural silk forms the ground 30. The vegetable fibres extend through the silk and form the same design 29 on the lower surface *b* of the silk illustrated in the lower part of Fig. 6; the upper surface *a* may be dyed with a dye which has a given action on the ordinary silk, making the ground 30; it differs in its effect on the artificial silk forming the design 29, with the result that 10 the color of the design 29 will be brought out in contrast with the color ground 30. The other surface *b* of the fabric may be dyed with an entirely different color which also affects the artificial silk on the surface *b* 15 differently from the way it affects the natural silk surface 30, thus producing the pleasing effect of a material having two contrasting ground colors with designs of colors differing in shade from said ground colors; 20 however, instead of dyeing the lower surface with a dye which differentiates the artificial silk design 29 from the ground 30, a dye may be selected which has substantially the same effect both on the artificial silk and on 25 the natural silk, so that the fabric will present the pleasing appearance of having grounds of different colors on each side thereof, with the design on the artificial silk in a different tone on one side thereof, but 30 substantially eliminated from the other side thereof.

Fig. 7 illustrates color effects produced by printing; in this case the double-tone fabric is printed with a design such as the leaf 31, 25 the color of which penetrates through the surface *a* to the surface *b*, as illustrated diagrammatically by the zone 32. The color effects here obtained may be additive; that is, the printing color may add to the ground 40 color, thereby changing the color of the printed design on both the sides *a* and *b*; thus, if the side *a* is red and the side *b* is yellow, and the design 31 is printed in yellow, said design will appear orange on the 45 red side *a*, while on the yellow side *b* it will substantially disappear; if the design is printed with another color such as black, it will appear black on both sides; when, as 50 described above, the color of the printed design is the same as that of one of the faces, it makes no striking contrast on the face which is the same color as the design, so that the fabric presents the appearance of being printed on one side with contrasting 55 colors, but on the other side is all of the same color with the design in shadow effect or substantially eliminated (although upon close examination the design may be traced since it is in darker color than the surrounding ground). One or both of the surfaces *a* and *b* may be colored with so-called direct dyes, and the printing can be effected with hydrosulphite with or without a basic dye with the result that the design can be printed 60 in colors which are different from the sur-

rounding ground; when the side *a* is colored with a direct dye and the other with a basic dye and the design 31 is printed by extracting, it will extract only from the side *a*, but not from the side *b*, thereby producing 70 a novel effect.

In Fig. 8 I show accordion pleating made in accordance with the invention which presents the novel characteristic that different surfaces of the material are colored different 75 colors on each side thereof, as well as different colors on the opposite sides thereof, and the colors on the opposite sides thereof may be entirely different from those on the first-mentioned side; thus, the surface 33 80 may be green, the surface 34 yellow, the under-surface 35 which is under the surface 33 may be yellow, and the under-surface 36, which is under the surface 34 may be orange; this is accomplished by 85 exposing a vat-dyed piece of goods colored yellow and accordion pleated to a color cloud on each of its faces, one color cloud being blue and forming a green with the yellow, and the other cloud being red and forming an orange with the yellow, thereby 90 coloring the surfaces 33 green, and the surfaces 36 orange.

In Fig. 9 I have shown a so-called ombre effect produced by exposing the material to 95 clouds of varying density, or by exposing portions of the material to clouds of different color; zones 37 and 38 may be dark blue, and the zone 39 may be a light blue; this is obtained by forming the color cloud 100 densest at the sides and weakest at the center; if the cloud is densest at one side, the material will be colored darkest at said side and lightest at the other side. In the case where the color is permitted to penetrate 105 through the material the under side *b* will present a similar surface; where the material is subjected to color clouds of different colors, zones 37, 38 and 39 on the surface *a* 110 will be of different colors; where these colors do not penetrate to the surface *b*, zones 39, 40 and 41 can also be of colors different from the zones 37, 38 and 39. The gradation of color in passing from one zone to another is gradual, and not a sharply defined line; the dotted lines herein being merely diagrammatic, and not intended to indicate a sharp line of demarcation.

In Fig. 10 I show stencil effects indicated 115 by the stencil design 50. The effects obtained with stencil devices vary widely and some will now be described; the design 50 is made by covering the surface *a* or the fabric at the point 50 so that the color cloud 120 does not descend upon the point 50, but 125 protects the original material from the color cloud, so that the design 50 presents the color of the original material; assuming the original material to be vat-dyed yellow, and subjected to a red color cloud on the side *a*, 130

the ground of the material will be orange, but the design will be in the original yellow; assuming the side *b* to be exposed to a blue color cloud, the ground will be colored green which will be darker at the point where the ground of the side *b* overlaps the ground of the side *a*, but at the stencil point the design 51 will appear in a different green owing to the fact that there is no red behind it on the surface *a*. Still more complex effects can be obtained if a stencil is also employed in connection with the dyeing of the side *b*, in which case the portions of the design 51 and additional portions 52 indicated in dotted lines can also be maintained the original yellow; as a result, the fabric will consist of the following color combination; on the surface *a* the red and yellow are mixed to form orange, with the yellow portion 50; on the surface *b* yellow and blue are mixed to form green, with the design 51 and 52 in original yellow.

In Fig. 11 I show a fabric which is vat-dyed and colored only on one side; for instance, the material is vat-dyed yellow and colored only by means of a cloud on one side exposed to a red cloud, so that it is orange on one side indicated by 51 and yellow on the other indicated by 52. Each of the threads will be fully colored, but each thread which enters the orange color zone will contain orange colored portions.

In Fig. 12 I illustrate a product which is colored on one side only but the color can be seen on the other side to such an extent as to tint the other surface; a piece of white silk is exposed to a red color cloud and colored red as indicated by 53; surface 54 is pink and forms a desirable contrasting color with the red surface 53.

The process of making this fabric can be either that set forth in the prior application Serial No. 692,762, or any of the applications herein referred to, but in order that the invention may be better comprehended, I will now proceed to describe the process and apparatus for making this fabric in accordance with prior application 692,762, and with particular reference to Figures 13 to 15 of the drawings.

Referring to the drawings, it will be seen that 10 represents a table bearing thereon a removable support 11 upon which the material 12 to be dyed is placed. The material here represented is adapted to serve as a dress length, and is laid flat and without wrinkles or folds upon the support 11, to which it is attached at its edges as shown, by suitable thumb tacks. 13 represents a box-like cover or hood which is seated on the table 10 and encloses the cloud of atomized dyeing matter held in suspension. 14 represents an air-brush of well-known character, such as a "Wold" air-brush, connected to a tank 15 or other source of compressed

air, and the tank 16 or other source of liquid dye. 17 is a shield running longitudinally of the hood and dividing it into two chambers, the spray chamber (*a*) and the cloud chamber (*b*), the shield being interposed between the spray and the support 11 on which the material is supported, and protecting the fabric from the action of the spray. 18 represents doors to permit inspection, and the insertion and withdrawal of the support 11 and the material thereon, and the removal of the trough 19. It will be noted that the lower portion of the shield forms this trough 19, which is slightly inclined as seen in Figure 2, so should the coloring matter collect in this trough in any quantity, it can be drawn off through the tap 20. It is to be particularly noted that the roof of the hood 13 has curved portions 21 in order to shape the cloud of atomized dye to predetermined form, thereby assisting in insuring an even or homogeneous coloring of the material.

The dye in liquid form is contained in the container 16 and in the form of air-brush here illustrated, it is drawn into the nozzle by aspiration, but it will be obvious that the dye may be fed into the air-brush in any usual manner, as by gravity, for example. The liquid dye is prepared in the same manner as for the usual vat dyeing processes, except that the solution is considerably more concentrated. The degree of concentration depends upon the final tint of color desired; for example, I have obtained good results with the use of a half ounce to one ounce of the dye, to a quart of the other liquid constituents of the dyeing mixture.

The air-brush 14 is provided with the usual needle valve 22 for regulating the extent of orifice thereof, and a valve 23 is provided in the line between the air-brush and the source of dye supply or tank 16 in order to control further the amount of color supply if desired. The amount of air and dye supply can be varied within a wide range by operating the needle valve 22 of the air-brush 14, and the pressure of the atomizing air by means of the cut-off and pressure regulating valve 23^a being preferably supplied at a pressure of about 30 pounds. In most cases, this regulation will be sufficient, but it may also be desirable to provide for the further regulation of the quantity of the dye supplied by means of the aforesaid valve 23. It will be obvious that the contents of the mixture emitted from the mouth of the air-brush is under the positive control of the operator, and that he can determine with exactitude the conditions obtaining in the spray; as a consequence, the cloud formed from this spray will be controlled by the operator as to its pressure and density, and it is further controlled as to its shape by the shape of the

hood; it is further controlled as to the quantity of dye present in proportion to the quantity of air present, and represents a substantially homogeneous mass of extremely fine particles of liquid dye held in suspension in the air. It is to be noted that the point of formation of this cloud is in front of the spray, which spray is not directed on to the fabric, but on the contrary, is shielded from the fabric by means of the shield 17, which prevents the coloring matter from coming into contact with the fabric directly from the mouth of the air-brush, or in the form of a spray; in other words, the fabric is not subjected to the direct action of the air-brush spray itself, or to the dropings or spattering of the air-brush, but only to the action of the cloud. The cloud can be controlled, and also held substantially uniform, as a result of which, the conditions existing in the dye chamber can be maintained substantially constant during the operation of the process.

I find it advantageous to provide curved 25 guide portions 24 located at the side and at the end of the trough opposite from that which supports the air-brush, which serve as guides to the particles in the formation of the cloud.

30 While I have here illustrated only one air-brush, it will be apparent that any suitable number of such brushes may be employed as is desired, and that these may be arranged in any suitable or convenient location.

A preferred operation of the improved method and apparatus will now be described with reference to the drawings and including the diagram of Figure 15.

40 The silk is first dried, if it is not already dry enough, by being placed in a suitable heating chamber (C), where it may be heated to the desired extent. The support 11 with the material 12 thereon is placed in the chamber (B), and subjected to the action of the cloud, which cloud is maintained by the continuous operation of the air-brush during the dyeing process. Once the cloud has been formed, and is being maintained,

45 it is not necessary to stop the operation of the air-brush after the piece of material has been colored to the desired extent, as this piece of material can be withdrawn, and another piece of material placed in the dyeing chamber through the right-hand door 18. The slight disturbance of the cloud caused by the opening of the door 18 is not sufficient to materially affect the coloring operation.

50 The extent of penetration of the dye into the fabric depends upon the length of time the material remains within the chamber, the amount of dye in the spray, and the nature of the dye. Complete penetration can be effected by leaving it in long enough, but if it is not desired to penetrate

more than a predetermined amount, as will be the case where the process is employed for coloring articles on both sides, which appears to be one of the most valuable uses of the process, the material will be removed 70 from the dyeing chamber before the penetration of the dye has exceeded a desired point, and thereafter it may be dyed on the opposite side thereof by placing it in a second apparatus similar to the apparatus just described, as illustrated diagrammatically in Figure 3, wherein E represents the apparatus for dyeing a piece of fabric one color, for example, blue, while F is the apparatus for dyeing the material with a second color on 80 the opposite side thereof; in this same diagram G represents an intermediate apparatus for heating or drying the material after it has passed through the first dyeing chamber, and D a steaming apparatus for steaming the fabric to set the dye, after it has been placed on the second chamber F, and colored thereon on the other side thereof. As illustrated in Figure 4 in diagrammatic cross-section, the materials or silk colored in 90 accordance with the present invention presents the characteristic that the dye penetrates the surface to a substantial extent, and this extent is preferably so predetermined that in the case of light fabrics, the 95 penetration on both sides is substantially equal to a full dyeing of the material.

It will be apparent from this description of my improved process that the silk is not in all cases merely coated, but is actually 100 penetrated by the dye to such an extent, that the silk possesses highly desirable qualities and compares with silk ordinarily in use; the color will not come out after fixing to any substantially greater extent than is the 105 case with the ordinary fabrics now dyed in vats, and the fabric presents on each surface an homogeneously and differently colored face, which makes it possible to employ the fabric for a large variety of commercial purposes; for example, lamp shades, ladies' 110 blouses, in which the collars and cuffs are formed by turning over the material, umbrellas and other uses.

It will be noted that in accordance with 115 the preferred manner of carrying out the process, the material is steamed in the usual steaming apparatus after having been dyed on both sides, so as to set the dyes; the fabric is otherwise treated in the manner usual 120 in the dyeing art.

It will be apparent that, if desired, a stencil 26 (shown in dotted lines, Fig. 1) can be placed over the material 12 in order to secure the imprint of a design thereon, and that this design may be printed in colors if positive and negative stencils are used, in which case, it becomes necessary to provide a third or fourth dyeing chamber according 125 to whether three or four colors are to be em- 130

ployed. In such case, the part which is colored in the first coloring chamber is protected by a stencil in the second coloring chamber, and the material is then colored 5 on the other side in the manner described above.

I wish it to be clearly understood that all the illustrations herein shown are merely diagrammatic and are not intended to indicate 10 the extent of penetration of the dye into the fabric which will vary according to a number of factors. It will also be obvious that the invention is not limited to the specific forms hereof as herein described, 15 but can be varied in a wide range without departing from the ambit of the invention and scope of the claims.

By the expression "cloud-dyed" which appears hereinafter in the present claims, I 20 mean dyed by means of a cloud of finely atomized particles of dye liquid, which cloud does not contain or form drops which fall on the fabric and are large enough to appear to the naked eye as "spots" on the 25 fabric, which "spots" show a deeper shade of color as compared with the surrounding field of the same color produced by the deposition on the fabric of the fine particles in the cloud; nor does this cloud contain 30 drops large enough to soak completely through the fabric so as to show a spot on each side of the fabric; nor do the particles of dye liquid in the cloud strike against the fabric directly from a spray.

35 The air-brush or atomizer selected for the carrying out of this process must be capable of atomizing the liquid dye into minute particles which are suspended in the air or gas; artists' air-brushes of the Wold type 40 have been found to give good results; drops issuing from the air brush are separated from the smaller particles which form the cloud, and the cloud particles come gently to rest upon the fabric and do not strike 45 against it with appreciable velocity.

In the claims which follow, I use the expression "permeable" to cover such goods as will be completely penetrated by the impingement or projection of drops thereon, 50 that is, the drops applied to one side soak through and wet the other side, and I include in this category, among other fabrics, silks such as tulles, crepes, satins, rayons and other light weight fabrics.

55 What I claim is—

1. A permeable two-tone textile fabric dyed substantially uniformly with one dye one face thereof to form a substantially even color ground and a different dye on the 60 other face thereof to form another substantially even color ground, threads running from one face to the other having portions dyed with one dye and other portions dyed with the other dye, and the color ground being free from "spots".

2. A permeable piece-dyed two-tone single-weave textile fabric which is colored throughout its thickness by strata of dyes of different color to form different and substantially even color grounds, the dye exposed at one surface being of one color, and the dye exposed at the other surface being of another color, and the color face being free from spots.

3. A permeable two-tone textile fabric 75 dyed with one dye on one face thereof and a different dye on the other face thereof, the threads running from one face to the other having portions dyed with one dye, other portions dyed with the other dye, and portions which are not dyed at all, each face being substantially uniform as to the evenness of its color.

4. A permeable two-tone textile fabric each side of which presents a distinct color 85 or tone different from the color or tone on the other side of the fabric, which fabric is made of threads all of the same raw material with cross threads running from one surface to the other, and each cross thread 90 having portions which correspond with the different colors or tones of the surfaces of the fabric.

5. A permeable two-tone textile fabric dyed with one dye on one face thereof and a 95 different dye on the other face thereof to form substantially even color grounds, the threads running from one face to the other having portions dyed with one dye and other portions dyed with the other dye, said color 100 ground bearing a design thereon.

6. A permeable single-weave two-tone textile fabric in which the threads are made of the same material, and in which the fabric bears a design thereon, the color of the design as it appears on one side of the two-tone fabric being different from the color of the design as it appears on the other side of the two-tone fabric.

7. A permeable piece-dyed two-tone textile fabric in which the threads are made of the same material, both surfaces of said fabric bearing definite uniform color effects, and the color effect on one surface being different from the color effect on the other 115 surface.

8. As an article of manufacture, a single-weave two-tone textile fabric having substantially even but differently colored grounds on each face thereof, each of said 120 faces bearing designs, and all of the threads of said fabric being made of the same material.

9. A single-weave piece-dyed two-tone textile fabric in which each of the cross 125 threads of the fabric is colored different colors throughout its length, the dyes forming said two-tone effect and coloring said threads being set in the fabric, and the color faces being free from undesired spots.

10. A permeable textile fabric presenting a surface on one side which is vat-dyed and a different color surface on the other side which is both vat dyed and cloud-dyed.
11. A permeable piece-dyed textile fabric having a side thereof colored to form a substantially even color ground by a dye which partially penetrates the fabric and is set in the fabric.
12. A two-tone textile fabric, presenting a surface on one side which is vat-dyed and a different color surface on the other side which is both vat dyed and cloud-dyed, the dyes being fast in the fabric.
13. A piece-dyed textile fabric, the thickness of which is partially penetrated by the dye to form a color surface presenting an un-spotted and substantially even color ground formed by color-cloud dyeing.
14. As an article of manufacture, a fabric dyed in the piece and having two strata of color, one color forming a substantially even color ground on one face thereof and the other forming a separate and substantially even color ground on the other face thereof, the dyes forming said color grounds being fast in the fabric.
15. As a new article of manufacture, a textile fabric presenting a color ground which is cloud dyed so that the dye but 30 partially penetrates the thickness of the fabric to form a color ground devoid of spots.
16. As a new article of manufacture, a textile fabric presenting a color surface 35 which is cloud-dyed by means of a dye so that the dye but partially penetrates the thickness of the fabric to form a color ground devoid of spots, the dye forming said color ground being set in the fabric. 40
17. As a new article of manufacture, a textile fabric presenting a color surface which is color cloud dyed and devoid of spots and bearing a design thereon, the dyes forming said color surface being fast in 45 the fabric.
18. As a new article of manufacture, a two-tone cloud dyed fabric with the dye set in the fabric.
19. As a new article of manufacture two- 50 tone cloud dyed fabric.

In testimony whereof, I have signed my name to this specification.

PIETER MIJER.
